Patented Nov. 29, 1966

206,349

COMBINATION T-SQUARE AND LEVEL

Boyd D. Barbee, 1941 63rd Ave.,
Sacramento, Calif. 95822

Filed Nov. 16, 1965, Ser. No. 88,117

Term of patent 14 years

(Cl. D52—6)

FIGURE 1 is a side elevational view of a combination T-square and level, showing my new design;

FIGURE 2 is a perspective view;

FIGURE 3 is a bottom plan view;

FIGURE 4 is a fragmentary sectional view, the plane of the section being indicated by the line 4—4 in FIGURE 1;

FIGURE 5 is a fragmentary sectional view, the plane of the section being indicated by the line 5—5 in FIGURE 1; and

FIGURE 6 is a front elevational view thereof.

I claim:

The ornamental design for a combination T-square and level, as shown.
